BRIQUETTING MACHINE

Richard W. Dinzl, Narberth, Pa., assignor to
Baldwin-Southwark Corporation, a corpora-
tion of Delaware

Application March 18, 1937, Serial No. 131,693

17 Claims. (Cl. 25—34)

This invention relates generally to hydraulic presses and more particularly to an improved hydraulic briquetting machine.

Various types of briquetting machines, particularly of the mechanical type, have heretofore been proposed and used but they have been deficient in various respects especially when used in certain ranges of capacity, for then, the necessary gears, toggle mechanism and frame structure involve a high initial cost as well as require a very large amount of floor space.

It is one object of my invention to provide an improved hydraulic briquetting machine which is relatively simple and comparatively inexpensive in construction, maintenance and operation, and yet has all of the desired qualities of speed and maximum compressing action combined with ruggedness, durability, compactness and ease of handling as well as accessibility of parts. The machine herein disclosed is especially applicable for briquetting metal shavings although its principles of operation and construction may be used for other materials.

A further object is to provide an improved control system for a briquetting machine whereby an improved predetermined sequence of operations may be effected with ease, positiveness and dispatch together with minimum wear and tear on the machine.

Other objects and advantages will be more apparent to those skilled in the art from the following description of the accompanying drawings in which:

Fig. 1 is a plan view of my improved machine;
Fig. 2 is a vertical section of the main ram taken substantially on the line 2—2 of Fig. 1;

Fig. 2a is a vertical section of the other end of the machine forming a continuation of Fig. 2 and taken substantially on the line 2a—2a of Fig. 1;

Fig. 3 is a transverse section taken substantially on the line 3—3 of Fig. 1;

Fig. 4 is a horizontal section taken substantially on the line 4—4 of Fig. 2a to show the hydraulic stripping cylinders and plungers;

Fig. 5 is an end elevation viewed in the direction of arrow 5 in Fig. 2a;

Fig. 6 is a diagrammatic outline of the piping diagram and control mechanism for the various press elements;

Fig. 7 is a modified arrangement of air operating pullback cylinders for the plunger and mold casings.

In the particular embodiments of the invention such as are disclosed herein for the purpose of illustrating certain specific forms among possible

others that the invention might take in practice, I have shown a press comprising, Fig. 3, a cast base 6 having two parallel hollow portions 7 and 8 connected by a suitable integral transverse web 9. Located at the left end of base 6 in abutting relation thereto is a main operating cylinder structure generally indicated at 10 while the other end of the base has a stationary platen 11, Figs. 1 and 2a. The main cylinder structure has four ears generally indicated at 12, two at the bottom and two at the top, and platen 11 has similar ears generally indicated at 13. The platen and main cylinder are secured to base 6 by longitudinal tie rods 14 extending through the lower set of ears and the hollow portions 7 and 8 thereby to hold the cylinder and platen in firm abutting relation to the base. A similar set of rods 15 extend through the upper set of ears and also through a pair of rugged spacer members 16 and 17 interposed between the upper ears 12 and 13. Thus the cylinder and platen are firmly held in a very rugged manner against distortion in any direction due to the relatively large size of the hollow spacing columns 7, 8, 16 and 17.

Disposed within cylinder 10 is a maximum load ram 20 which is hollow to form a cylinder 21 for a stationary low load ram 22. This latter ram has a rod in threaded engagement 23 with a plate 24 which is bolted as at 25 to the closed end of cylinder 10. A suitable collar 26 is formed on the end of the ram to receive fluid pressure operating connections one of which communicates with a passage 27 leading to an operating chamber 28 and the other of which leads by a passage 29 to the second operating chamber 30 of the low load cylinder. A suitable packing gland 31 secured to ram 20 is interposed between the latter and ram 22 while another packing gland interposed between ram 20 and cylinder 10 is secured thereto.

Removably supported by the front end of ram 20 is a compressing plunger 33 having an enlarged preferably cylindrical flange 34 held in a suitable recess within ram 20 by a collar 35 bolted or otherwise suitably secured to ram 20. This plunger, Fig. 2a, extends forwardly into telescopic relation with a plunger casing 41 formed as part of a unitary hopper and mold structure generally indicated at 36. The front end of plunger 33, Fig. 2a, is provided with a removable material engaging portion 37 which has a stem 38 disposed within a suitable bore of plunger 33. A transverse wedge or other suitable transverse key 39 securely holds the parts 33 and 37 together, it being noted, however, that in the forward position of the plunger casing 41 (which is the posi-

tion shown in Fig. 2a), the main body portion of plunger 33 is disposed well within the bore 40 of casing 41. This casing is removably secured to the wall 42 of the unit 36.

5 The unit 36 has a hopper 43 to feed material into a laterally accessible material chamber 44 preferably substantially square in plan view, Figs. 1 and 2a. The unit is also mounted for longitudinal reciprocable movement by the provision, 10 Fig. 3, of lateral flanges 45 slidably supported in suitable guideways 46 formed on the upper surfaces of the hollow base portions 7 and 8. Suitable vertical flanges 48 have screws 49 threaded therein for laterally adjusting strips 50 which engage flanges 45 along an inclined guiding surface, certain of the bolts being omitted from Fig. 2a, for purpose of clarity, although their location is indicated by the reference numeral 49 therein.

15 The forward wall of unit 36 has a mold sleeve or 20 casing 52, Fig. 2a, removably secured thereto by a bolt and keeper ring construction 53.

20 A fixed backing wall or mold closing plunger 54 opposed to compressing plunger 33, is preferably adapted to be telescopically received in the 25 bore of mold sleeve 52, and is provided with a preferably circular flange 55 firmly held by a collar 56 in a suitable recess within platen 11. It will be noted that the bottom 57 of chamber 44 is preferably in alignment with the lowermost 30 portion of the cylindrical plunger bores in casings 41 and 52.

35 An air cylinder 58, secured to the outside of platen 11, has a piston 59 provided with a limit stop flange 59' engageable with a cooperating shoulder in the cylinder. The piston has separable abutting engagement with a diagonal crosshead 60 which is connected by rods 61 and 62 to suitable ears 63 and 64 respectively, Figs. 2a and 3, formed on the outside of the unit 36. The 40 rods are slidably supported in guide lugs 60' on air cylinder 58. Air pressure is maintained in cylinder 58 so as to constantly bias unit 36 to the right. To move unit 36 to the left as during a stripping operation, there is provided as shown in Fig. 4 a pair of hydraulically operated rams and 45 cylinders 65 and 66 secured to opposite sides of platen 11. The rams are connected by rods 67 to ears 68, Figs. 3 and 4, secured to the unit structure 36.

Operation

50 The pumping fluid connections as diagrammatically shown in Fig. 6, and also certain improved functional and structural aspects of the invention, will be more readily apparent from a description 55 of the sequence of operations. In the position of the parts as shown in Fig. 6, the plunger 33 is in its rearmost position and mold casing 52 is in initial telescopic relation with closing plunger 54. Assuming that the press is to be operated through 60 one cycle and then stopped, the normal position of cam follower 73 would be down out of engagement with the cam 75 secured to main ram 20, this disengagement being effected by withdrawal of a wedge member 72 which is shifted by 65 clockwise rotation of a hand lever 76. Hence to start the press, hand lever 76 is first moved counterclockwise to thrust wedge member 72 between a valve stem 74 and follower 73, thereby causing follower 73 to engage cam 75 and simultaneously move valve stem 74 and its control valve 71 downwardly. With valve 71 in its down position, air from any suitable source pipe 77 is admitted through a pipe 78 to a servo-motor air cylinder 79, thereby moving a valve 80 to a down position 70 in which it is automatically held by a pivotal

latch arm 81 engaging a groove in the valve stem. Thereupon hydraulic pressure from a suitable pump 83, preferably of any well-known constant speed positive displacement type with manual adjustment of the volume, is supplied through a pipe 84 and a valve 85 which was previously moved to its down position during the preceding cycle, to be described later, and held therein by a pivotal latch 85' engaging a valve stem groove. Fluid pressure from valve 85 then passes through 10 pipe 86, valve 80 and a pipe 87 to the small cylinder chamber 28 of the main operating ram. Simultaneously fluid pressure is supplied from the pump through valve 85 and a pipe 88 to the pullback chamber 30 of the main ram mechanism, 15 but due to the larger area of chamber 28, ram 20 will move forwardly pushing briquetting material from chamber 44, Fig. 2a, into mold 52. As the briquette 91, Fig. 2a, begins to compress, it offers increasing resistance to movement of 20 plunger 33 and its ram 20, with consequent increasing pump pressure until finally an automatic pressure responsive valve 89, Fig. 6, opens to admit full pressure from the pump through a pipe 90 to the large operating end of cylinder 10. This 25 will immediately give to the briquette a final pressing action under a large force. At any time during the compressing action if the frictional resistance between the briquette and the walls of the mold 52 should increase sufficiently, the 30 mold together with the whole unit 36 will, under the influence of this frictional force, bodily move forward in the direction of movement of the plunger. If this frictional force should not become sufficiently great to effect said bodily movement, the briquette will nevertheless be formed. Such frictionally induced movement is independent of the air cylinder and piston 58, 59 by virtue of the stop shoulder arrangement 59' limiting outward movement of piston 59 but permitting rod 40 61 and crosshead 60, Fig. 2a, to move freely to the right away from the now immovable piston 59. During a subsequent stripping operation, 45 however, the crosshead 60 will reengage piston 59 to push the same inwardly against the air pressure therein. In the position of the piston 59 as shown in Fig. 2a, sufficient clearance is left between the mold 52 and retainer collar 56 to permit said frictionally induced movement.

50 Pressure in the large end of main cylinder 10 is transmitted through a pipe 93 to a pressure responsive piston 94 which raises upon occurrence of a predetermined pressure in the main cylinder 10 to engage a link 95, thereby releasing both latches 81 and 85' through stop nuts 96 and a pivotal connection 97 between link 95 and latch 85'. Thereupon both valves 80 and 85 are raised by constant air pressure supplied from any suitable source to the under side of servo-motors 79 and 88. This places the stripper cylinders 65 in 60 operation by supplying pump fluid thereto through pipe 84, valve 85 and a pipe 99, whereupon mold 52 together with the remaining elements of unit 36 is moved to the left, Fig. 2a, thereby stripping the briquette 91 from mold 52, 65 it being understood that compressing plunger 33 at this time is fully within the mold 52 to serve as a stop against which the briquette reacts when pushed out of the mold. The plunger 33, in serving as a stop during the stripping operation, is 70 not necessarily stationary during this operation because when valve 85 is unlatched, the pullback chamber 30 is exhausted, through pipe 88 and port 85a, simultaneously with exhausting of fluid from the smaller main operating cylinder 28 75

through valve 80 and one of its exhaust ports 80a and with exhausting of fluid from main cylinder 10 through a filling check valve 103 to be described later. Because of the absence of any pressure in the main cylinder for resisting the rearward stripping force, it is seen that the compressing plunger may move rearwardly under this force depending upon the rate at which fluid is pushed out of the main cylinders 28 and 10 through the usual passages in valves 80 and 103.

The stripping movement of mold 52 to the left continues until a cam 100, suitably supported on the unit casing structure 36, engages and depresses a valve 101, whereupon air pressure from a suitable source is admitted to the top of servo-motor 98, thereby moving valve 85 to its down position in which it is automatically held by latch 85'. During this latching operation, rod 95 moves freely downwardly through latch 81, the nuts 96 moving away therefrom to provide a lost motion connection for subsequent operation of latch 81. The stripper cylinders 65 are now opened to exhaust through port 85b of valve 85 and simultaneously pump pressure is admitted from pipe 84 to pipe 88 and pullback cylinder 30, thereby withdrawing plunger 33 to its rearmost position to restart the next cycle of operation. When the stripping operation is complete, briquette 91 falls from the end of mold 52 into any suitable receptacle or conveyor. Also upon release of operating pressure from the stripping cylinder 65, air piston 59 will immediately move the unit 36 to the right until mold 52 has partial telescopic engagement with back- 35 ing plunger 54 preparatory for the next compressing operation. The extent of initial telescopic engagement with mold closing plunger 54 is determined by engagement of piston stop 59' with its cooperating shoulder on cylinder 58. Simulta- 40 neously with supply of pump pressure to the pullback cylinder, pump pressure is supplied through pipe 86 to a pipe 102 (valve 80 now being in its upper position) to raise a pilot piston of a filling check valve 103 and open the same to allow free flow of fluid from cylinder 10 past filling valve 103, as previously mentioned, to a pipe 104 and a filling tank 105, thereby facilitating rapid return of compressing plunger 33.

To effect continuous automatic operation, wedge member 72 is allowed to remain in the position shown so that when compressing plunger 33 is fully returned, cam 15, suitably carried by ram 20, engages follower 73 to depress valve 71 and admit fluid pressure to pipe 78 and servo-motor 79 to move valve 80 downwardly, thereby to connect control pipe 102 to exhaust pipe 80b with consequent reclosing of filling check valve 103. Simultaneously therewith pipe 86 is connected to pipe 87 for supplying pump fluid to small main cylinder 28 thereby to automatically repeat the cycle of operations, all as heretofore disclosed. If it is desired to stop the press when plunger 33 is withdrawn, handle 76 is moved clockwise to remove wedge 72 from between valve 75 stem 74 and follower 73, thereby preventing cam 15 depressing valve 71 which will be consequently held in its upper position by a spring or other suitable biasing means. With the valve 71 in its upper position, pipe 78 is connected to exhaust 70 108, thereby allowing valve 80 to be held in its upper exhaust position by the constant pressure below servo piston 79.

Fig. 7 modification.—In this arrangement, air cylinders 110 are suitably supported upon any stationary part of the press frame such as the

lower spacer members 7 and 8 while pistons 111 are provided with suitable shoulders 112 to limit the extent of outward movement. The pistons have abutting engagement with any suitable portion of the unitary structure 36 to normally bias the same to the right to effect closure of the mold by plunger 54. The plunger casing and mold unit 36 is adapted, however, to be moved further to the right under the influence of frictional contact between the briquette and the walls of the mold, entirely independently of pistons 111 whose flanges 112 limit the action of the pistons. It will be understood that these air operated pullback piston and cylinders take the place of the single pullback cylinder 58 in 15 the preferred form shown in Fig. 2a together with the elimination of the side rods 61 and 62 and crosshead 60 thereby providing a more compact machine.

From the disclosure herein it is seen that I have provided a briquetting machine that is relatively simple and economical in construction, operation and maintenance and is adapted to effectively compress a briquette with a minimum number of parts and operating movements thereof. It is also seen that my improved combined compressing plunger casing and mold casing with a laterally accessible material chamber therebetween, insures not only a rugged and simplified structure but also one in which the various elements are positively maintained in alignment at all times. The spacing members between the stationary platen and cylinder structure provide an extraordinarily rigid base support upon which the unitary hopper and casing structure 36 may be effectively longitudinally guided. These various advantages are coupled with my improved hydraulic operating means and the control system for effecting a predetermined sequence of operations with minimum loss of time and with maximum effectiveness.

It will of course be understood that various changes in details of construction and arrangement of parts may be made by those skilled in the art without departing from the spirit of the invention as set forth in the appended claims.

1. A briquetting machine comprising, in combination, a compressing plunger, an opposed mold closing plunger, a unitary structure having a compressing plunger casing and a mold casing with a laterally accessible material receiving chamber between the same, means for effecting relative telescopic movement between said closing plunger and mold casing to close the latter, hydraulically actuated means for moving said compressing plunger forwardly through said material chamber and into said mold to form and compress a briquette, and hydraulically actuated means for rearwardly moving said mold casing to effect a stripping action by having the briquette bear against the compressing plunger, said means for effecting relative movement between the mold casing and mold closing plunger, including means for bodily moving said unitary structure to effect said closing relation.

2. A briquetting machine comprising, in combination, a compressing plunger, an opposed mold closing plunger, a unitary structure having a compressing plunger casing and a mold casing with a laterally accessible material receiving chamber between the same, means for effecting relative telescopic movement between said closing plunger and mold casing to close the latter, hydraulically actuated means for moving said compressing plunger forwardly through said ma-

terial chamber and into said mold to form and compress a briquette, hydraulically actuated means for rearwardly moving said mold casing to effect a stripping action by having the briquette bear against the compressing plunger, and means for supporting said mold closing plunger in a stationary position at all times, while the means for effecting relative movement between the mold casing and closing plunger includes means for bodily moving said unitary structure to effect said closing relation.

3. A briquetting machine comprising, in combination, a compressing plunger, an opposed mold closing plunger, a unitary structure having a compressing plunger casing and a mold casing with a laterally accessible material receiving chamber between the same, means for effecting relative movement between said closing plunger and mold casing to bring the same into initial telescopic relation, hydraulically actuated means for moving said compressing plunger forwardly through said material chamber and into said mold to form and compress a briquette, and hydraulically actuated means for rearwardly moving said mold casing to effect a stripping action by having the briquette bear against the compressing plunger, said mold casing and closing plunger having provision to allow further telescopic movement induced by frictional contact between the briquette and mold during compressing of the briquette by the compressing plunger.

4. The combination set forth in claim 3 further characterized in that said means for initially effecting relative telescopic movement between the mold casing and its closing plunger includes air operated piston and cylinder mechanism.

5. The combination set forth in claim 3 further characterized in that said means for initially effecting relative telescopic movement between the mold casing and its closing plunger includes air operated piston and cylinder mechanism, and means for limiting the extent of operation of said air operated mechanism thereby to establish said initial degree of telescopic relation.

45 6. A briquetting machine comprising, in combination, a compressing plunger, a stationary mold closing plunger, a unitary structure having a compressing plunger casing and a mold casing with a material chamber between the same, means for moving said unitary structure toward said mold closing plunger so that the same is telescopically received in said mold casing to close the same, hydraulically actuated means for moving said compressing plunger forwardly through said material chamber and into said mold casing to form and compress a briquette, hydraulically actuated means for moving said unitary structure rearwardly to effect a stripping action by having the briquette react against said compressing plunger, and means whereby said compressing plunger is initially moved rearwardly at a slower rate than the movement of said unitary structure.

7. A briquetting machine comprising, in combination, a compressing plunger, a stationary mold closing plunger, a unitary structure having a compressing plunger casing and a mold casing with a material chamber between the same, means for moving said unitary structure forwardly to telescopically receive said closing plunger and thereby close said mold casing, means for moving said compressing plunger through said material space and into said mold casing to form and compress a briquette, means for moving said unitary structure rearwardly to effect a

stripping action by having the briquette react against the compressing plunger, and means for initially moving said compressing plunger rearwardly during said stripping action but at a slower rate of movement than that of said unitary structure.

8. A briquetting machine comprising, in combination, a compressing plunger, a stationary mold closing plunger, a unitary structure having a compressing plunger casing and a mold casing with a material chamber between the same, means for moving said unitary structure forwardly to close said mold casing by its closing plunger, means for moving said compressing plunger through said material space and into said mold casing to form and compress a briquette, means for moving said unitary structure rearwardly to effect a stripping action by having the briquette react against the compressing plunger, and means for initially moving said compressing plunger rearwardly during said stripping action but at a slower rate of movement than that of said unitary structure and after the stripping action is completed to effect a relatively rapid rate of rearward movement of the compressing plunger.

9. A briquetting machine comprising, in combination, a compressing plunger, a stationary mold closing plunger, a unitary structure having a compressing plunger casing and a mold casing with a material chamber between the same, air actuated means for moving said unitary structure forwardly to close said mold casing by its closing plunger, hydraulically actuated means for moving said compressing plunger through said material chamber and into said mold casing to form and compress a briquette, hydraulically operated pullback mechanism for said compressing plunger, hydraulic means for moving said unitary structure rearwardly upon a completion of a compressing operation thereby to effect a stripping action by having the briquette react against the compressing plunger, and means for relieving hydraulic pressure in said hydraulically actuated means and in said pullback mechanism during said stripping operation.

10. A briquetting machine comprising, in combination, a compressing plunger, a stationary mold closing plunger, a unitary structure having a compressing plunger casing and a mold casing with a material chamber between the same, air actuated means for moving said unitary structure forwardly to close said mold casing by its closing plunger, hydraulically actuated means for moving said compressing plunger through said material chamber and into said mold casing to form and compress a briquette, hydraulically operated pullback mechanism for said compressing plunger, hydraulic means for moving said unitary structure rearwardly upon a completion of a compressing operation thereby to effect a stripping action by having the briquette react against the compressing plunger, means for relieving hydraulic pressure in said hydraulically actuated means and in said pullback mechanism during said stripping operation, and means for supplying operating fluid to said pullback mechanism substantially upon completion of the stripping operation thereby to effect rapid withdrawal of the compressing plunger to its original starting position.

11. A briquetting machine comprising, in combination, a compressing plunger, a casing therefor, an opposed mold closing plunger, a mold casing therefor, means forming a material chamber between said casings, means for effecting rela-

tive movement between said closing plunger and mold casing to close the latter, hydraulically actuated means for moving said compressing plunger forwardly through said material chamber and into said mold to form and compress a briquette, hydraulically actuated means for moving said mold casing rearwardly to strip a briquette therefrom, hydraulically actuated means for moving said compressing plunger to its rearward position, and hydraulic control means for effecting a predetermined sequence of operations of all of said actuated elements so as to form and compress the briquette, initially relieve the compressing force on the briquette and then strip the same and return the elements to their original starting position.

12. The combination set forth in claim 11 further characterized in that the means for effecting relative closing movement between the mold casing and its closing plunger comprises a constantly operative biasing means.

13. A briquetting machine comprising, in combination, a compressing plunger, a casing therefor, an opposed mold closing plunger, a mold casing therefor, means forming a material chamber between said casings, means for effecting relative movement between said closing plunger and mold casing to close the latter, hydraulically actuated means for moving said compressing plunger forwardly through said material chamber and into said mold to form and compress a briquette, hydraulically actuated means for moving said mold casing to strip a briquette therefrom, hydraulically actuated means for moving said compressing plunger to its rearward position, hydraulic control means for effecting a predetermined sequence of operations of all of said actuated elements so as to form and compress the briquette, strip the same and return the elements to their original starting position, and means for automatically repeating the cycle of operations when all of the elements are returned to their original starting position.

14. The combination set forth in claim 11 further characterized by the provision of means for automatically repeating the cycle of operations when all of the elements are returned to their original starting position, or for effecting only a single cycle.

15. The combination set forth in claim 11 further characterized by the provision of a constantly operating pump for supplying fluid pressure

to all of the hydraulically actuated means, including connections between the hydraulic control means and said pump.

16. A briquetting machine comprising, in combination, a compressing plunger, a casing therefor, an opposed mold closing plunger, a mold casing therefor, means forming a material chamber between said casings, means for effecting relative movement between said closing plunger and mold casing to close the latter, hydraulically actuated means for moving said compressing plunger forwardly through said material chamber and into said mold to form and compress a briquette, hydraulically actuated means for moving said mold casing to strip a briquette therefrom, hydraulically actuated means for moving said compressing plunger to its rearward position, hydraulic control means for effecting a predetermined sequence of operations of all of said actuated elements so as to form and compress the briquette, strip the same and return the elements to their original starting position, said hydraulic actuating means for the compressing plunger including a main cylinder and a hollow ram therein, a stationary ram disposed within said hollow ram, means whereby said compressing plunger is initially moved forwardly by fluid pressure supplied to said hollow ram, and means responsive to a predetermined pressure in said hollow ram for automatically supplying fluid pressure to said main cylinder to effect a final movement of the compressing plunger.

17. A briquetting machine comprising, in combination, a horizontal base structure, a stationary platen secured to one end thereof, a main operating cylinder and ram mechanism secured to the other end of said base, a compressing plunger actuated from said main cylinder, an opposed mold closing plunger supported by said stationary platen, a unitary structure having a compressing plunger casing and a mold casing with a laterally accessible material receiving chamber between the same, means for longitudinally slidably supporting said unitary structure directly on said base, actuating means for moving said unitary structure toward said mold closing plunger to close the mold and for moving said structure rearwardly to strip a briquette against said compressing plunger, and means for controlling the operation of said main ram so that it may be withdrawn following said stripping action.

RICHARD W. DINZL.
